COLLAPSIBLE DISPLAY STAND

Application filed February 6, 1931. Serial No. 514,035.

The present invention has reference to collapsible display stands, and comprehends certain improvements in the structures embodied in my copending applications.

5 The invention has for one of its objects the provision of a display stand constructed to permit of it being readily collapsed for both shipping and storage purposes, and when set up for use provides an exceedingly attractive 10 and substantial support for the merchandise to be displayed.

It is the primary object of the present invention to provide a display stand of the above mentioned character, which when set 15 up for use possesses the desired strength and stability.

In carrying out the invention, I contemplate the provision of a display stand having a supporting shelf of step-like formation, 20 adapted to be effectively braced and secured to adjacent walls of the stand, to afford the latter a maximum degree of strength and rigidity.

For this purpose, I preferably employ 25 combined supporting and reinforcing strips of angle formation in cross section, adapted to be used in pairs and arranged above and below each shelf-like portion, along the line of fold thereof, and effectively but removably secured to the adjacent walls of the 30 stand, thereby materially increasing the strength and rigidity of the latter, and at the same time allow the stand to be conveniently collapsed when desired.

35 The invention will be better understood from the following detail description when read in connection with the accompanying drawings, the invention residing in the construction, combination and arrangement of parts as claimed.

In the drawings forming part of this application like numerals of reference indicate similar parts in the several views and 45 wherein:

Figure 1 is a fragmentary perspective view of one embodiment of the invention.

Figure 2 is a vertical sectional view therethrough.

away to illustrate one of the shelf supporting flaps.

Figure 4 is a side elevation of the stand collapsed.

Figure 5 is a sectional view on line 5—5 55 of Figure 4.

Figure 6 is a view of one of the combined supporting and reinforcing strips.

Figure 7 is an enlarged fragmentary detail view. 60

Figure 8 is a fragmentary perspective view of a pair of the combined supporting and reinforcing strips.

Figure 9 is a fragmentary sectional view of a modified construction. 65

Figure 10 is a view showing a blank of material from which the walls of the stand can be formed.

Figure 11 is a plan view of the shelf as a separate element. 70

Figure 12 is a fragmentary sectional view of a modified construction, showing one way of attaching the shelf to the walls of the stand.

Figure 13 is a similar view of a further 75 modified form of the invention.

Figure 14 is a top plan view of Figure 13.

Figure 15 is an edge elevation of the shelf collapsed. 80

Figure 16 is a fragmentary sectional view similar to Figure 12 showing another way of supporting the shelf structure on the walls of the stand.

The present invention resides in the provision of a display stand having a supporting shelf of step-like formation, adapted to be effectively supported between the walls of the stand, and in a manner to afford the latter maximum strength and rigidity. Consequently, before entering into a detail description of what is herein illustrated, I desire to have it understood that the invention contemplates a stand of the character above mentioned, wherein the supporting shelf may constitute a separate element, suitably attached to and supported by the walls of the stand, or formed as an integral part thereof. Furthermore the stand may be constructed of either corrugated or solid material of any character whatsoever, and may vary in size 90 95 100

and cross sectional contour without departing from the inventive idea.

In the particular embodiment of the invention illustrated in Figures 1 to 8 inclusive, the stand embodies a front wall 10, side walls 11 and a rear wall 12. These walls may all be of the same height, or of relatively different heights, although the upper edges of the side walls 11 are preferably inclined rearwardly as at 15. The stand is open at both ends, and in this form of the invention, the adjacent edges of the front wall 10 and side walls 11 are connected in any suitable manner, preferably by means of strips of adhesive material 14.

The front wall 10 also includes a portion separated from the side walls and capable of being arranged horizontally between the side walls to form a shelf. As clearly illustrated in the drawings, the stand can be conveniently collapsed for both shipping and storage purposes, in which event the shelf is folded parallel with the front wall 10. The entire structure can also be easily and quickly set up for use when desired.

For this purpose the shelf is capable of being folded along spaced parallel lines to provide a shelf of step-like formation, and it is of course to be understood, that the shelf 30 can not only vary in size, but folded along parallel lines to provide any desired number of shelf-like portions 16 and 16'. Obviously each portion 16 is arranged horizontally, while each portion 16' is disposed vertically, and these shelf-like portions can vary in 35 dimensions within the scope of the present invention.

I have also illustrated in Figure 9 a modified construction, wherein the shelf is folded 40 to provide opposed series of shelf-like portions 17 and 18 respectively, and an intermediate shelf-like portion 19, the shelf-like portions of each series being stepped.

In accordance with the present invention, I provide a display stand of the class in question, which when set up for use possesses a relatively high degree of strength and rigidity. With this object in view I contemplate bracing the shelf-like portions 16 and 16' from opposite sides, and connect these portions with the opposed side walls of the stand. In this connection I preferably employ a plurality of combined supporting and reinforcing strips of angle formation, adapted to be used in the manner illustrated. In other words these strips are used in pairs, and arranged above and below each shelf-like section, and along the line of fold between the portions 16 and 16' thereof. For instance, the lowermost strip of each pair is positioned to receive the adjacent fold edge of the particular shelf section, having one of its branches 20 engaging the under side of the shelf-like portion 16 and its other branch 21 disposed to engage the inner side of the ver-

tical portion 16' of the particular shelf section. The other or uppermost companion strip is arranged in the angle of the shelf-like portions 16 and 16' and has its corresponding branch 20 reposing upon the shelf-like portion 16, while its branch 21 engages the outer side of the vertical portion 16 of the shelf section. These combined supporting and reinforcing strips are adapted to be passed through substantially L-shaped openings 22 formed in the opposed side walls 11. Each strip is slotted longitudinally from its opposite ends to provide bendable lugs 23 which are adapted to be bent against the side walls 11, after the strips have been properly associated with the shelf-like portions, as clearly illustrated in Figures 7 and 8. By reason of this construction, the shelf in its entirety is effectively connected to the opposed side walls 11 of the stand, thus holding these parts fixed relatively, and affording the stand maximum strength and rigidity. The final horizontal shelf-like portion 16 is supported by the rear wall 12, preferably by means of flaps 24 cut or stamped from the rear wall 12. The combined supporting and reinforcing strips can be very easily and quickly associated with the shelf-like portions for use, and also separated therefrom with a minimum of effort to permit the stand to be collapsed when desired.

As shown in Figure 10 the walls of the stand can be formed from a single blank of material, and the front wall 10 connected to one of the side walls 11 by a single strip of adhesive material 14, in contradistinction to the structure above described. Furthermore, in accordance with this embodiment of the invention, the shelf constitutes a separate element, capable of being folded along spaced parallel lines to provide shelf sections, each including the portions 16 and 16' respectively. For use the shelf proper can be suitably attached to the front and rear walls of the stand, although for shipping or storage purposes the shelf can be flattened or collapsed as shown in Figure 11. While various means may be employed for attaching the shelf to the front and rear walls of the stand, I have illustrated in Figure 12 how the outermost shelf-like portion 16 can be attached to the front wall by adhesive tape indicated at 25. The final shelf-like portion can of course be attached to the rear wall of the stand in a similar manner. Then again the shelf proper can be supported on the front and rear walls of the stand by means of flaps 24 as shown in Figure 13. These flaps as above stated are stamped from their respective walls. The respective walls of the stand can be of the same or relatively different heights, and I have illustrated by dotted lines 27 in Figure 10 how these walls can be cut to vary their height and degree of inclination of the upper edges of the side walls.

In Figures 13 and 14 I have disclosed a further modified form of the invention, which differs from the other forms in the specific construction of the supporting shelf. In this embodiment of the invention the shelf also constitutes a separate element adapted to be supported on the front and rear walls of the stand, either by the flaps 24 as shown in Figure 13 or by adhesive tape 32 as in Figure 16 or in any other suitable manner. The shelf is characterized, however, by sections arranged in overlapping relation and hinged together in any desired manner. For this purpose I preferably employ strips of adhesive tape 28. Each section is also divided by a fold line 29 into shelf-like portions 30 and 31 respectively so that the shelf in its entirety can be set up for use in the manner illustrated in Figure 13, or collapsed as shown in Figure 15. By reason of this construction, it is manifest that each vertically disposed portion 30 of each shelf section extends an appreciable distance above the horizontally disposed portion 31 of the adjacent shelf section, thereby defining separate or individual compartments for the attractive display of various assortments of merchandise. Then again, the vertically disposed portions 30 of the respective shelf sections prevent any article of merchandise from slipping from one compartment into the adjacent compartment. Of course in all forms of the invention, the companion angle brace elements as disclosed in Figure 6 are preferably employed for the purposes above stated. When the stand is collapsed as shown in Figure 4 the supporting shelf is arranged parallel with the front wall, irrespective of whether the shelf constitutes a separate element or an integral part of the stand.

While it is believed that from the foregoing description the nature and advantages of the invention will be readily apparent, I desire to have it known that I do not limit myself to what is herein illustrated or described and that such changes may be resorted to when desired as fall within the scope of what is claimed.

What is claimed is:

- 50 1. A collapsible display stand comprising spaced walls, a collapsible shelf arranged between said walls and including foldably connected sections to provide a plurality of stepped shelf-like portions, and companion angle-shaped elements arranged at the fold of each shelf-like portion to effectively brace the latter and connected with the adjacent walls to rigidly support the shelf-like portions relatively thereto.
- 60 2. A collapsible display stand comprising spaced walls, a shelf removably supported between said walls and including foldably connected sections to provide a plurality of stepped shelf-like portions, companion elements of angle formation in cross section ar-

ranged along the fold of each shelf-like portion to effectively brace the latter, and means carried by said elements for detachably securing the same to the adjacent walls.

70 3. A collapsible display stand comprising spaced walls, a shelf supported between said walls and including foldably connected sections to provide a plurality of stepped shelf-like portions, companion angle-shaped elements arranged along the fold of each shelf-like portion to effectively brace the latter, and bendable lugs formed on the ends of said elements and adapted to be passed through and bent against the adjacent walls to detachably connect the elements thereto.

75 4. A collapsible display stand comprising spaced walls, a shelf supported between said walls and including foldably connected sections to provide a plurality of stepped shelf-like portions, two opposed walls having aligned openings, companion angle-shaped elements received by said openings and arranged along the fold of each shelf-like portion to effectively brace the latter, and means carried by said elements for detachably securing the same to the opposed walls.

80 5. A collapsible display stand comprising pairs of opposed spaced walls connected along their longitudinal edges by fold lines, whereby said walls can be collapsed diagonally therefrom to provide a flat compact article, a shelf arranged between said walls and formed to provide a plurality of stepped shelf-like portions, means for supporting the front and rear ends of the shelf from one pair of said walls, and separable means for bracing each shelf-like portion from its opposite sides and along the fold thereof and detachably connected with the other pair of said walls.

85 6. A collapsible display stand comprising pairs of opposed spaced walls connected along their longitudinal edges by fold lines, whereby the stand can be collapsed from the corners to provide a flat compact article, a shelf positioned between the walls and including foldably connected sections to provide a plurality of stepped shelf-like portions, means for supporting the shelf from one pair of said walls, and angle-shaped bracing elements arranged at opposite sides and along the fold of each shelf-like portion and detachably connected with the other pair of walls of the stand.

90 7. A collapsible display stand comprising spaced walls, a shelf arranged between said walls and including a plurality of overlapping foldably connected shelf sections arranged to provide a plurality of stepped shelf-like portions with the vertical member terminating above the horizontal member, and means for removably supporting the shelf on the walls of the stand.

95 8. A collapsible display stand comprising pairs of opposed walls connected along

100

their longitudinal edges by fold lines, whereby the stand can be collapsed diagonally from the corners thereof to provide a flat compact article, a shelf positioned between said walls and including a plurality of overlapping foldable shelf sections to provide a plurality of shelf-like portions with the vertical member of each portions terminating above the horizontal member thereof, and

10 means for supporting the shelf on the walls of the stand.

9. A collapsible display stand comprising spaced walls, a shelf arranged between said walls and including a plurality of hingedly connected overlapping foldable shelf sections to provide horizontally disposed shelf portions and vertically disposed portions, the vertically disposed portions terminating above and in advance of the adjacent horizontal portions, and means for supporting the shelf between said walls and holding the shelf rigid relatively thereto.
